UNITED STATES PATENT OFFICE.

HAROLD H. SIMMS, OF ROCHESTER, NEW YORK, ASSIGNOR TO AUTO STROP COMPANY, OF NEW YORK, N. Y., A CORPORATION OF NEW YORK.

RAZOR.

1,133,329.

Specification of Letters Patent. Patented Mar. 30, 1915.

Original application filed April 17, 1909, Serial No. 490,564. Divided and this application filed September 23, 1909. Serial No. 519,220.

To all whom it may concern:

Be it known that I, HAROLD H. SIMMS, of Rochester, in the county of Monroe and State of New York, have invented certain new and useful Improvements in Razors; and I do hereby declare the following to be a full, clear, and exact description of the same, reference being had to the accompanying drawings, forming a part of this specification, and to the reference-numerals marked thereon.

The present invention relates to safety razors, the subject matter of this application having been divided from an application filed by me on April 17, 1909, Serial No. 490,564.

An object of this invention is to provide a construction which will permit the blade to be thrown to a position away from the guard with but few manipulations on the part of the user, so that the blade may be sharpened.

To these and other ends the invention consists in certain improvements and combinations of parts all as will be hereinafter more fully described, the novel features being pointed out in the claims at the end of the specification.

In the drawings: Figure 1 is a transverse section of one embodiment of the invention; Fig. 2 is a longitudinal section, and Fig. 3 is a side view showing the device adjusted for stropping.

In the illustrated embodiment of the invention there is provided a blade holder for detachably securing a blade 1 which may have two cutting edges. This blade holder preferably comprises a supporting member or plate 2 curved or concaved on its under side so as to pass freely over a strop or other sharpener and carrying positioning means on its upper surface, such as pins 3 which are adapted to pass through openings in the blade 1. The blade is clamped to the supporting member, in this instance by a plate 4 which co-operates with the blade between the two edges of the latter, a screw 5 or other clamping device serving to hold the plate to the supporting member.

The blade holder is preferably supported by a guard frame comprising in this instance a longitudinally curved or concaved plate 6 formed to fit the under surface of the plate 2 and carrying two guards 7 formed by notched longitudinal edges of the plate.

The connection between the guard frame and the blade holder may be in the form of a pivot or hinge 8 arranged at one end of the holder and of the guard frame and adapting the blade holder to swing away from the guards, preferably about an axis extending transverse to the direction of the width of the blade so that both edges of the blade may be exposed for stropping or sharpening. This construction permits the blade holder to lie in a plane transverse to or at an angle to the plane of the guard frame, as shown in Fig. 3, being maintained in this position by depending stop or projection 8^a at the hinged end of the holder co-operating with the under surface of the guard frame and limiting the movement of the blade away from the guards, and a spring latch 9 co-operating with said stop or projection to retain the latter in engagement with the guard frame. The blade may be held in co-operative relation with the guards by a spring latch 10 formed on the other end of the guard frame to engage the free end of the blade holder.

The handle of the razor is preferably secured to the guard frame between the two guards and at an angle to the plane of the guard frame. In this instance it comprises a portion 11 secured to the guard frame at one end and surrounded by a grip portion 12 which preferably may be made either to rotate on portion 11 or to remain rigid therewith. In this instance the inner end of the grip portion has a clutch portion 13 to co-operate with a clutch portion 14 on the guard frame, a nut 15 working on the outer screw threaded end of the handle to force the grip endwise into engagement with clutch portion 14. During shaving the grip should be rigidly secured to the guard but during stropping or sharpening it is preferable that the grip rotate for when the handle and blade holder lie parallel, the blade will shift automatically to present another edge to the strop at the beginning of each stroke.

In order that the blade clamping means may be easily operated, the handle portion 11 is made hollow and receives a rotary shaft or stem 16 which is held against axial movement by a collar 17 at the inner end of the handle and a thumb piece 18 at the outer end of the handle. This stem serves as an operating means for the blade clamp.

ing device and for this purpose has a non-circular end 19 adapted to enter a pocket in the screw 5 when the blade holder is moved into coöperative relation with the 5 guard. It is preferred that the screw 5 be journaled in the supporting plate 2 and held against removal therefrom by a collar 20 so that the screw is not liable to be lost or mislaid.

10 The shaving position of the parts are shown in Figs. 1 and 2 and if it is desired to sharpen the blade the blade holder with the blade is released from the latch 10 and swung to the position shown in Fig. 3 where 15 the stop 8^a engages latch 9 and holds the parts in this position, the handle grip 12 being released either previously or subsequently to the movement of the blade holder. If the razor now be brought to a sharpener 20 only one face of one of its edges will co-operate with the sharpener when the razor is moved in one direction and one face of the other edge will be engaged on the movement of the razor in the other direction. 25 The other faces of both edges may be sharpened by reversing the position of the blade in the holder. To remove the blade from its holder it is only necessary that the blade holder be swung back into coöperative relation with its guards. Then the clamping 30 screw will be engaged by the end of the rotary stem which, if rotated, releases the plate 4.

A safety razor constructed in accordance 35 with this invention permits the blade holder to be moved quickly from coöperative relation with its guard or guards in order that the blade may be sharpened in the holder which supports it during the shaving operation. The handle is so connected to the 40 razor that it may be utilized for effecting the automatic shifting of the blade at the end of each stroke, so that another edge is brought into engagement with the sharpener. This 45 handle also carries means which facilitates the removal of the blade from the holder or its reversal within said holder and the clamping means is so arranged that both the upper and the under surface of the blade holder is smooth for shaving or stropping. 50

I claim as my invention:

1. In a safety razor, the combination with 55 a guard, a handle rigidly secured thereto, and a blade, of a supporting member for the blade pivotally carried by the guard to swing about an axis extending transversely of the cutting edge of the blade, and means for clamping said blade to the supporting member, so that the blade is held to said member 60 when the latter is swung away from the guard.

2. In a safety razor, the combination with 65 a guard frame carrying a pair of guards, a handle rigidly secured to said frame, and a double-edged blade, of a supporting member

for the blade pivotally secured to the guard frame near one end of the cutting edges and movable on said pivot about an axis extending transversely of the cutting edges of the blade to carry said blade away from the 70 guards, and means for clamping said blade to the supporting member so that the blade is held to the member when the latter is swung away from the guards.

3. In a safety razor, the combination with 75 a guard and a blade, of a blade holder movable about an axis extending transversely of the cutting edge of the blade in the holder to carry the blade away from the guard, and a device for retaining said holder against 80 movement when out of coöperative relation with the guard to permit the blade to be stropped.

4. The combination with a guard and a 85 blade, of a supporting member for holding the blade in coöperative relation with the guard, means for securing said supporting member with said blade therein with the length of the blade at an angle to the length of the guard, and means for clamping said 90 blade to the supporting member so that the blade is held to said member when the latter is out of coöperative relation with the guard.

5. In a safety razor, the combination with 95 a guard, a blade and a handle secured to the guard and extending in a plane transverse to the length of the guard, of a supporting member for securing the blade in coöperative relation to the guard, means for securing said supporting member, with the blade 100 therein, with the length of the blade transverse to the length of the guard, and means for clamping said blade to the supporting member so that the blade is held to said member when the latter is out of coöperative 105 relation with the guard.

6. In a safety razor, the combination with 110 a guard, a handle secured thereto and extending transversely thereof, and a blade, of a supporting member for the blade, means for securing said supporting member in coöperative relation with the guard for shaving, means for securing said supporting member with its length transverse to the 115 length of the guard and parallel with the handle, and means for clamping said blade to the supporting member so that the blade is held to said member when the latter is parallel with the handle.

7. In a safety razor, the combination with 120 a guard, a handle secured thereto and extending transversely to the plane thereof, and a blade, of means for securing said blade in coöperative relation with the guard for shaving, and means for rigidly supporting said blade on the guard with its length at an angle to the length of the guard.

8. In a safety razor, the combination with 125 a guard frame having a pair of guards thereon, a handle secured to the guard frame 130

symmetrically between the guards and transverse to the plane thereof, and a double-edged blade, of a supporting member for co-operating with a blade between the two edges thereof and pivoted to the guard frame to swing about an axis transverse to the length of such guard frame, and means for clamping said blade to the supporting member so that the blade is held to said member 10 when the latter is swung away from the guard.

9. In a safety razor, the combination with a guard frame having a pair of guards thereon, a handle secured to the guard frame transverse to the plane of the latter, a double 15 edged blade, and a blade holder for such blade, of means for securing the blade holder to hold the two edges of the blade in co-operative relation with the guard, and means 20 for securing the blade holder so that the latter with the blade therein will lie with its length at an angle to the length of the guard frame.

10. In a safety razor, the combination with a guard frame having guards along 25 opposite edges thereof, a handle secured between the guards and transverse to the plane of the guard frame, and a double edged blade, of a blade holder for said blade pivoted at one end to one end of the guard frame to turn about an axis extending transverse to the cutting edges of the blade in the holder.

11. In a safety razor, the combination with a guard frame having guards along 35 opposite edges thereof, a handle secured between said guards and transverse to the plane of the guard frame, and a double-edged blade, of a supporting member for the blade pivoted to turn about an axis extending transverse to the cutting edges of the blade in the holder, means for clamping said blade to the supporting member so that the blade is held to said member when the latter 40 is swung away from the guard frame, and a latch for securing the blade supporting member in co-operative relation with the guard for shaving.

12. In a safety razor, the combination with a guard frame having guards along 50 opposite edges thereof, a handle secured between said guards and transverse to the plane of the guard frame, and a double edged blade, of a blade holder for said blade pivoted at one end to one end of the guard frame to turn about an axis transverse to the cutting edges of the blade in the holder, and a stop arranged to position the blade holder with the blade therein at an angle to 55 the plane of the guard frame.

13. In a safety razor, the combination with a guard frame having guards along opposite edges thereof, of a handle secured between said guards and transverse to the plane of the guard frame, and a double 65 edged blade, of a blade holder for said double edged blade pivoted at one end to one end of the guard frame to turn about an axis extending transverse to the cutting edges of the double edged blade in the holder, and a latch for holding the blade holder at an angle to the plane of the guard frame.

14. In a safety razor, the combination with a blade holder having a blade clamping means carried thereby, and a guard, one of said elements being movable relatively to the other, the clamping means being effective when the guard and blade holder have been relatively moved one away from the other, of operating means for the clamping means, said operating means being carried by the guard so as to be disconnected from the clamping means on the relative movement of the guard and the blade holder. 80 85

15. In a safety razor, the combination with a guard and a blade, of a blade holder movable relatively to the guard having blade clamping means carried thereby and embodying a screw for securing the blade while the blade holder is located away from co-operative relation with the guard, and operating means for said screw carried with the guard and disconnected from the screw when the blade holder has been moved away 90 95 from the guard.

16. In a safety razor, the combination with a guard, a handle secured thereto and a blade, of a blade holder movable relatively to the guard and having blade clamping means for securing the blade when the blade holder is away from the guard, and a rotatable shaft on the handle for operating the clamping means. 100

17. In a safety razor, the combination with a guard, a hollow handle secured thereto, and a blade, of a blade holder movable relatively to the guard and having a screw clamping means for securing the blade when the blade holder is away from the guard, 105 and a shaft mounted in the handle and adapted to operate the screw when the blade holder is lying in co-operative relation with the guard and to be disconnected from the clamping means when the blade holder is 110 115 moved away from the guard.
